Atty.

UNITED STATES PATENT OFFICE.

TIMOTHY ROGERS, OF SPRINGFIELD, OHIO, ASSIGNOR, BY MESNE ASSIGNMENTS, TO THE ROGERS FENCE COMPANY, OF SAME PLACE.

LAWN-MOWER.

SPECIFICATION forming part of Letters Patent No. 333,550, dated January 5, 1886.

Application filed August 6, 1884. Serial No. 139,803. (No model.)

To all whom it may concern:

Be it known that I, TIMOTHY ROGERS, a citizen of the United States, residing at Springfield, in the county of Clark and State of Ohio, have invented certain new and useful Improvements in Lawn-Mowers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in lawn-mowers.

My invention relates to that class of lawn-mowers in which a series of rotary knives are operated to cut the grass; and it consists in the combination, with the lawn-mower, of a certain kind of friction-gearing for driving the cutting apparatus. A one-way clutch is attached to the knife-reel shaft, in which spring-actuated pins engage the friction-pinion on one side of the case inclosing the rubber wheel, this case forming a section of the clutch.

Figure 1 is a top view of a lawn-mower with my improvement embodied therein. Fig. 2 is a side elevation of the same with a portion of the ground or driving wheel broken away to the interior of the same. Fig. 3 is a section through line *x*, Fig. 2, with the drive-wheel replaced.

The construction of the frame and cutting apparatus and the location of the latter in front of the axial line of the drive-wheels are the subject of another application, (No. 139,802, filed August 6, 1884,) and I do not therefore claim them in this.

40 Drive-wheels are used with an internal V-shaped groove in the rim. A pinion of rubber of reverse shape to the groove engages the latter and is driven thereby. This pinion is on the shaft of the knife-reel and in connection with the clutch, and the latter form the principal parts of my improvement.

A are the ground-wheels or drivers. These are formed with an internal V-shaped groove, *b*, on the inside of the rim. This 50 groove is not central with the rim, but is nearer the inside edge, a rib, *b'*, dividing the

groove from a space, *a*, between the outer wall of the wheel and this rib, within which the end of the shaft *C* extends, enough room being allowed for a pin in the end of the shaft outside the vertical plane of the rib, there being a flat-threaded nut, *a''*, screwed upon the sleeve *b''* of the case to compress the rubber pinion *a'*, which, as will be seen by Fig. 3, is on this sleeve between the nut and the inner wall of the case *a''*, and is forced against the latter wall by the pressure of the nut, so as to cause it to expand into the groove *b* when adjusted. Only the bevel portion of the pinion engages the groove. The inner wall of case *a''* is a part of 65 clutch *C'*, which latter is about twice the diameter of shaft *C* and forms the journal *c* for the shaft end which revolves in a bearing, *c'*, in the end disks, *B*, of the frame *A'*. The latter is connected in front by the guard-bar *d'*, 70 and in the rear by the curved hound-piece to which the tongue-bar or handle is attached. The ground-wheels *A* are pivoted on spindles extending from the centers of the disk-shaped ends *B*.

75 In operating the machine, as the wheels *A* rotate the groove *b* engages the pinion *a'*, pins *e* engaging the grooves represented by the dotted line *e'* across shaft *C*, Fig. 3, and when the ends of these grooves are reached 80 the pinion and shaft turn together rotating the knife-reel.

The use of friction-gearing is old, and I do not claim it broadly; but the combination therewith of the pin-clutch in the manner described affords the most direct mode of driving the knife-reel shaft, and is believed to be new.

I therefore claim as my invention—

1. In a lawn-mower, the ground-wheel having the V-shaped groove therein, the adjustable friction-pinion engaged therewith, the pin-clutch, the knife-reel, and the frame, said pin-clutch forming the journal of the shaft of said knife-reel, and the case of said friction-pinion forming a section of said pin-clutch.

2. In a lawn-mower operated by friction-gearing, as described, the combination, with the knife-reel, of the drive-wheel having the internal V-shaped groove, the rubber pinion, and means for adjusting the same, the pinion-case; the pin-clutch, both of the latter being

attached to the shaft of said knife-reel, and said pinion-case forming a section of said pin-clutch, and the frame provided with a bearing for said pin-clutch, which latter forms the journal of said knife-reel, as set forth.

3. In a lawn-mower, the drive-wheel having the V-shaped groove therein, the adjustable rubber pinion, the pinion-case, the pin-clutch, said pinion-case forming a section of the latter, the knife-reel shaft, and the frame

having the disk-shaped end, and a bearing in the latter for the clutch-journal of the knife-reel shaft, as set forth.

In testimony whereof I affix my signature in presence of two witnesses.

TIMOTHY ROGERS.

Witnesses:
